UNITED STATES PATENT OFFICE.

HENRY DISCHINGER, OF ELMORE, OHIO.

PAINT-BRUSH PROTECTOR.

SPECIFICATION forming part of Letters Patent No. 271,814, dated February 6, 1883.

Application filed October 20, 1882. (No model.)

To all whom it may concern:

Be it known that I, HENRY DISCHINGER, of Elmore, in the county of Ottawa and State of Ohio, have invented a certain new and Improved Paint-Brush Protector; and I do hereby declare that the following is a full, clear, and complete description thereof.

This improvement relates to a protector for brushes for painting, varnishing, &c., the nature of which consists of a case or box adapted to the form and size of the brush, which case consists of two sections or parts hinged or jointed together at one end, so as to open for the reception of the brush and to close upon it, being held by means of clamps or otherwise, by which means the brush will be protected from dirt and dust, and the hair or bristles will also be prevented from springing apart or curling. This article may also be used by the manufacturer for protecting new brushes for the trade.

For a more full and complete description of the said invention reference will be had to the following specifications and to the annexed drawings, making part of the same.

Figure 1 is a side view of the case and brush therein; Fig. 2, a view of the front thereof; Fig. 3, a sectional view of the case in direction of the line $\alpha\alpha$, Fig. 2, with the brush therein; Fig. 4, a view of the upper end, showing the brush.

Like letters of reference refer to like parts in the several views.

It is well known among those engaged in the art of painting that brushes become seriously injured, and for some work rendered useless, by the hair or bristles becoming curled and sprung apart, which is particularly the case with fine brushes. It is the practice to place brushes together in water, with the hair or bristles resting on the bottom of the vessel containing the water. In this way the bristles become softened, bent, and twisted out of place, and need cleaning before being used, because of the mingling of the colors from the brushes when mixed together with the dirt in the vessel. These objections are avoided by the herein-described protector, which may be made of sheet tin, brass, or any other suitable material.

In the drawings, A represents the said pro-

tector, which consists of a case or box, either 50 angular or tubular, adapted to the form and size of the brush. The one herein described is wedge-shaped, and in two sections, B C, which are connected together by a hinge or pin joint, D, Figs. 1 and 2. This joint allows the case 55 to be opened, as indicated by the dotted line a, Fig. 1, to receive the brush, and is then closed. The section B forms a cover for the section C, and is provided with flanges E at the sides and end, which lap on over the sides and end of 60 section C, as seen in Figs. 1, 3, and 4. The two sections when closed are held together by clips or hooks G H, hinged at I I to the section B, and extending across the open end of the case and hook on over the edge of the section 65 B, as seen at J J, Figs. 2 and 3. By this means the two sections of the case are clasped together at the open end, while the sections are connected together at the other end by a hinge-joint at D D, substantially as set forth. 70

In using the protector it is opened, and the brush, whether dry or charged with paint, is laid in the section B with the hair or bristles straightened out, which is readily done by drawing the brush a little longitudinally in the case 75 in the direction of the open end thereof, which will cause the bristles to lie smoothly and straight with each other, thereby preventing the curling and springing of the bristles.

It will be seen that the brush, when in the 80 case, is confined upon all sides by it, according to the form or shape of the article, as the cases may be made or shaped to receive the different forms of brushes in use without departing from the nature of said invention. 85

After a brush has been used and charged with paint or varnish it may be inclosed within the case and carried in the pocket, or otherwise, without imparting its paint outside of the case, and when in the case it may be placed in 90 water, as is usually done, and for the same purpose, which will keep the brush in good condition and free from dirt and the paint from other brushes in the same water-vessel.

What I claim as my invention, and desire to 95 secure by Letters Patent, is—

1. A paint-brush protector consisting of a hollow case formed in two sections, and hinged

together at one end and provided with hooks or clamps at the other to secure the two sections together, arranged to allow the said sections to open and close for the reception, retention, and removal of the brush, substantially as set forth, and for the purpose set forth.

2. A paint-brush-protecting case consisting of two sections, B C, hinged together, with one section provided with flanges to lap over the sides of the adjoining section, and fastened to-

gether by clips or hooks for holding the brush within the case, arranged in the manner substantially as set forth.

In testimony whereof I affix my signature in presence of two witnesses.

HENRY DISCHINGER.
